HINGE BEARING OF DISCONNECT SWITCH

Gustave E. Heberlein, Bryn Mawr, Pa., assignor,
by mesne assignments, to I-T-E Circuit Breaker
Company, Philadelphia, Pa., a corporation of
Pennsylvania

Application December 5, 1951, Serial No. 259,917

10 Claims. (Cl. 200—48)

1

My present invention relates to hinge bearings of disconnect switches and more particularly to hinge bearings adapted to carry current between the frame and the hinge casting of disconnect switches of the type shown in application Serial No. 145,389 filed February 21, 1950.

In many prior constructions, it was thought necessary that a flexible shunt be placed between the fixed terminal and the movable contact arm. This movable flexible shunt was thought to be essential to ensure that a good path be available for the current flowing from the contact arm to the ground terminal.

This required weatherproofing or other types of protection, but when this weatherproofing was incompletely done, it sometimes happened that the shunt tended to corrode, crystallize and break.

The primary object of my invention is to provide a simplified current carrying element between a fixed terminal and a movable contact arm of a disconnect switch so that there be no need for flexible connecting elements.

Another object of my invention is the provision of means whereby threaded pins are clamped to the hinge casting so that the current may efficiently flow from the hinge casting through the hinge pin to the frame casting.

Another object of my invention is the provision of contact arms of spring-like contacting metals to act as current paths between the hinge pins and the frame casting and to maintain appropriate contact pressure.

A further object of my invention is the placement of said movable current carrying connections in a fully weatherproofed and fully protected housing.

Another object of my invention is a contact carrying member which is readily inspectable or dismantlable to permit inspection.

These and many other objects and advantages of my invention will become apparent in the following description and drawings in which:

Figure 1 is a side view of the disconnect switch incorporating this invention.

Figure 2 is a vertical section of this invention showing the clamped threaded pin and spring tension arms.

Figure 3 is a plan view of this invention.

Figure 4 is an exploded view of this invention showing the various members of this invention.

Figure 5 is a vertical section of a modified version of this invention showing a heavy compression spring for producing a high pressure electrical contact.

Figure 6a is a schematic cross section showing

2

the contact engagement achieved in the modified version of the hinge bearing.

Figure 6b is a schematic view of an annular contact showing the similarity in principle between the threaded hinge contact of Figure 6a and the annular contact.

Referring now to Figure 1, I have here shown a disconnect of the type disclosed in application Serial No. 145,389 filed February 21, 1950 in which the disconnect switch 10 is mounted on the base 11 which is a suitable longitudinal structural support, in this case shown horizontally arranged for a horizontally or upright mounted disconnect switch.

10 The base 11 has secured thereto in any suitable manner as by the insulator spacers 12 and 13 the stationary upright supporting posts 14, 15 on the upper portions of which are mounted insulators 16, 17.

15 Base 11 is also provided with the bearing 20 appropriately secured thereto in any suitable manner as by the bolts 21 and carrying the rotatable vertical shaft 22 to the upper end of which is keyed the insulator 23 for rotation with the vertical shaft or post 22.

20 Below insulator 23 there is keyed to the shaft 22 the crank 30 secured thereto in any suitable manner as by the bolts 31 connected to the flange or crank plate 32. Bolts 21 which secure the bearing 20 in position also secure the stop plate 34 in position, the stop plate being provided at opposite ends with the adjustable stops 37 which engage at either end with the stop 38 on the operating crank 30.

25 35 While stops 37 are herein provided, the construction and operation of my novel switch is such that it may operate properly without the stops at individual poles; in such case, the stops would be provided at the operating means for the entire switch.

30 40 Where stops are eliminated at all points, then the switch may be operated by crank 30 to close and then open by a single continuous movement in one direction to establish a contact momentarily and then break it.

45 50 Shaft 22a extends above the insulator 23 as effectively a continuation of vertical shaft 22 being, however, spaced therefrom by insulator 23. Crank 40 at the upper end of shaft 22a is preferably integral therewith and, therefore, rotates therewith.

55 Crank 40 extends horizontally or at least parallel with the base supporting structure 11 and rotates in the horizontal plane. Crank 40 is shown herein as tubular although it may have

any desired cross-section consistent with the mechanical loads imposed thereon. The outer end of crank 40 is flattened at 41 and is provided with a circular opening 42 through which pin 43 may pass.

A clevis member 44 receives extension 41, connection being made by pin 42. Clevis 44 is integral with the threaded extension 50 which enters into the tapped opening 51 in the forked link 52. The threaded extension 50 is so arranged that as the threaded extension 50 rotates with respect to the forked link 52 and its tapped opening 51, it has linear movement with respect thereto. Forked link 52 has a pair of arms 54 at the ends opposite the tapped opening 51 which are secured to the blade crank 61 of sleeve casting 62 by pin 60a. The blade support sleeve casting 62 carries the tubular switch blade 63 secured therein and rotatable therewith.

The outer end of the tubular switch blade is flattened at 64 (Figure 1) and is provided with appropriate contacts 65 engageable with the stationary contact jaws 66. The blade support sleeve casting 62 is mounted for rotation around its longitudinal axis on an extension of the hinge casting 70. The hinge casting 70 is in turn rotatably mounted by the hinge bearings indicated generally at 72 on the forked frame casting 73.

The particular hinge bearing utilized for this purpose at this point constitutes the essence of the present invention and will be discussed in detail below.

The frame casting 73 has a horizontal section 74 secured in any suitable manner as by the bolts 75 to the top of insulator 16. The sides 76 extend back to the solid portion 77 which is provided with an opening (not shown) appropriately recessed to form a bearing for crank 40 and its shaft.

The solid portion 77 of the base casting 62 then extends beyond to form the terminal 80 to which appropriate leads may be connected.

The stationary contact 66 comprises the plurality of contact blades 90, 91 on each side biased toward each other by the spring support members 92, 93 and so arranged that when the blade 65 enters at an angle to the horizontal position during the closing operation, it will clear the blades 90 on each side.

These contact members are so arranged, however, that when the blade is rotated from the open to the closed position, the blade 65 in turning to the horizontal position will spread the contacts 90 and 91 on each side against the tension of springs 92 and 93, creating the desired contact pressure.

The spring blades 92, 93 are current conducting and are connected in any suitable manner as by the bolts 98 to the base plate 99, which in turn is mounted in any suitable manner as by bolts 200 at the top of insulator 11. The base 99 of stationary contact structure 66 has an extension 201 which serves as a terminal block or connecting member.

Thus, when the disconnect switch is in the closed position of Figure 1, current enters the terminal 80, passes through the frame casting 73 to the hinge bearing 72, then through the current carrying connection in the hinge bearing 72 to the hinge casting 70, from the hinge casting 70 to the contact valve 63, then through the contact 65 on the contact blade 63 to the stationary contact elements 90, 91 and then through the base 99 to the terminal extension 201.

The particular hinge bearing utilized for this

purpose at this point constitutes the essence of the present invention. This hinge bearing which constitutes the current carrying connection between the frame and the hinge casting for the tubular blade 63 is shown specifically in the cross-sectional view of Figure 2, the side view of Figure 3 and the exploded view of Figure 4.

Referring, therefore, to these figures, the legs 76 of the frame 73 are each provided with a substantially circular thickened area 100 at the upper right-hand corner of each thereof.

Each of the thickened reinforced areas 100 is provided with a transverse bore 101 constituting a hinge pin bearing for purposes hereinafter described, each of the members 100 being also counterbored at 102 and internally threaded at 103 at the counterbore to receive the enclosing cup 104, also for purposes hereinafter described.

The hinge casting 70 is also essentially a bifurcated member having the arms 110. Each of the arms 110 of the hinge casting 70 is provided adjacent its free end with an internally threaded circular opening 112, the material of the arm 110 beyond the openings 112 on each side having the extension lugs 113, 114 and the opening 112 being divided or slotted at 115; lugs 113, 114 are provided with the openings 116, 117.

A threaded bolt 120 may be passed through the openings and tightened in place by the nut 122 or any appropriate arrangement of lock nuts, thereby clamping the lugs 113 and 114 together and diminishing the size of the main threaded opening 112 on each arm 110.

In assembling the hinge casting on the frame 73, the arms 110 of the hinge casting are aligned with sections 76 of the frame 73 so that openings 112 on each side of the arms 110 are aligned with the smooth bore openings 101.

The hinge pin 130 on each side is then passed through opening 112 and when the threads 131 of hinge pin 130 engage threads of opening 112, the hinge pin 130 is rotated further through opening 112 until the hinge pin 130 passes through opening 101 and projects beyond the same as shown in Figure 2.

This operation is performed on each side, the end of each hinge pin 130 being provided with any appropriate means for rotating the same as, for instance, a hexagonal recess 135.

After each of the hinge pins 130 is in the appropriate positions indicated in Figures 2 and 3, arms 110 are tightened on bolt 120 clamping the lugs 113 and 114 together, thereby diminishing the size of opening 112 and clamping the surface of opening 112 tightly onto the threaded surface 131 of hinge pin 130; by this means the hinge pin 130 is at 131 substantially integrated for current conducting purposes with the arm 110 so that an efficient current carrying connection is established, the pin 130 being essentially rigid with the arm 110.

The end 140 of hinge pin 130 projecting into the counterbore section 102 of the reinforcement 100 is of smaller diameter than the main portion of the hinge pin 130 and is provided with the annular contacting surface 142, the said contacting surface being of a suitable silver or silver compound alloy or sintered product adapted to make an efficient moving contact.

The smooth section 145 of hinge pin 130 is adapted to ride in the bearing 101 of reinforcement 100 of leg 76 on each side, thereby providing an effective hinge or rotatable arrangement. A sealing gasket 145a is provided between the smooth section 145 of pin 130 and bearing 101.

5

After the hinge pins have been positioned in place, the substantially cylindrical member 150 secured to cup 160 is placed into the counterbore sections 102. It is here necessary to point out that cylindrical member 150 is assembled in cup 160 prior to assembly of disconnect 10 to make an electrical joint and a unified structure. The cylindrical member 150 has a solid copper flange 151 and a plurality of spring legs 152 created by and separated from each other by a plurality of slots 153 in the original cylinder.

The legs 152 since they are preferably of a spring-like contacting metal such as beryllium copper can be efficient current carrying members while at the same time they can maintain appropriate contact pressure.

Each of the legs 152 may be provided with a silver or silver composition button 155 at the inner surface of the ends thereof which register with the annular contact section 142 on the hinge pin 130.

Thereafter the sealing cup 160 having the recess chamber 161 and the exterior threaded section 162 is screwed into position in counterbore section 102 engaging the threads 103.

Preferably a weather-excluding gasket 170 is provided against which the end of the wall of cup 160 may seat so that together with gasket 145a it makes the contacts housing 100—160 fully weatherproof and protected. The annular flange 151 of the cylindrical cup member 150 is a tight force fit in the chamber 161 of cup 160 so that an efficient current carrying path is established from flange 151 to the wall of cup 160 or other suitable connection means.

Appropriate no-oxid or other material which will protect the contacts from corrosion may be included in the chamber 102—161. The current path from the main disconnect contact blade from the hinge casting 70 to the frame 73 is, therefore, through each of the arms 110 and surfaces 112 and 131 to the hinge pin 130; then from contact surface 142 of the hinge pin to contact button 155 on the cylindrical member 150, then through flange 151 to the interior wall of cup 160, then through the threads 162 and 103 to reinforcing member 100 on each of the arms 76, through the arms 76 to the frame 73 and then to the terminal 80.

Although current may flow through the meeting surfaces 145 and 101, this is not the intended current carrying path nor can the surface be designed to carry current since an appropriate good current by-pass is provided with appropriate contacting surfaces by means of the cylinder 150, contact buttons 155 and the annular surface 142. In fact, an insulating bearing of Bakelite or oil impregnated similar material may be used between meeting surfaces 145 and 101, if desired.

Thus, pigtails of any kind are avoided. The current carrying connection at the hinge is through fully enclosed weatherproofed and fully protected movable contact members.

A modified version of this invention is shown in Figure 5 where arms 110 of hinge casting 70 are clamped in a manner similar to the one described in connection with Figures 2, 3 and 4 to hinge pin 230. Hinge pin 230 is provided with two threaded extensions 231 and 250, one at each end. Threaded extension 231 engages threaded portion 112 of hinge casting 70 to which it is clamped as previously shown. The surface of center section 240 of hinge pin 230 is smooth so that it can ride in the bearing 101 of rein-

6

forcement 100 of leg 76 on each side, thereby providing an effective hinge or rotatable arrangement.

Reinforcement 100 is provided with a cylindrical counterbore 102 which is internally threaded at 103 to receive the sealing cup 260.

Metallic cup 260 of cylindrical section is provided at its upper end 251 with threads 252 which engage threaded surface 103 of reinforcement 100 when cup 260 is rotated with respect to reinforcement 100 of leg 76. Reinforcement 100 is provided with a cylindrical recess 253 which serves to receive a cylindrical sealing member or gasket 254 to make the cylindrical counterbore 102 air-tight and weatherproof.

Cup 260 also has an internally threaded opening 256 which is engaged by the threaded extension 250 of pin 230. A nut 257 threaded on extension 250 of pin 230 serves to produce a high pressure engagement of the type shown hereinafter in connection with Figure 6a between the threaded portion 256 of cup 260 and the threaded extension 250 of pin 230.

It is now evident that the current will flow (see Figures 1 and 5) from terminal 80 through member 73 to legs 76 and thence through the threaded contacts 103 and 252 to the sealing cup 260, from the sealing cup 260 through threaded contacts 256 and 250 to hinge pin 230, from hinge pin 230 through threads 231 and 112 to hinge casting 70 and thence through blade 63 to the movable contacts 65 and finally to the stationary contacts 90 and 91 and to the other terminal 201.

The type of contact achieved between cup 260 and member 76 is shown in Figure 6a. It is easily seen by comparing Figure 6a with Figure 6b showing a well-known annular contact that in the contact engagement shown in Figure 6a three times the contact area is available where three threads are in engagement. Hence, screw contact is more efficient.

In the foregoing I have described my invention solely in connection with specific illustrative embodiments thereof. Since many variations and modifications of my invention will now be obvious to those skilled in the art, I prefer to be bound not by the specific disclosures herein contained but only by the appended claims.

I claim:

1. A switch having a frame and a movable contact arm; said contact arm being radially and axially rotatable with respect to said frame; a current carrying connection between said frame and said movable contact arm; said contact arm having two internally threaded extensions; a partly threaded current carrying pin; means securing the threaded part of said pin to said threaded extensions of said contact arm; a cylindrical recess in said frame having a partly threaded surface and a bearing coaxial to said recess; said current carrying pin rotating in said coaxial bearing; a cylindrical contact cup, said cup being externally threaded to engage the threaded surface of said cylindrical recess; a set of contact fingers, said contact fingers being connected to said contact cup, said contact fingers being biased into current carrying engagement with said current carrying pin; means sealing said current carrying connections.

2. A switch having a frame and a movable contact arm; said contact arm being radially and axially rotatable with respect to said frame; a current carrying connection between said frame and said movable contact arm; said con-

tact arm having two internally threaded extensions; a partly threaded current carrying pin; means securing the threaded part of said pin to said threaded extensions of said contact arm; a cylindrical recess in said frame having a partly threaded surface and a bearing coaxial to said recess; said current carrying pin rotating in said coaxial bearing; a cylindrical contact cup; said cup being externally threaded to engage the threaded surface of said cylindrical recess; a set of contact fingers; said contact fingers being connected to said contact cup; said contact fingers being biased into current carrying engagement with said carrying pin.

3. A switch having a frame and a movable contact arm; said contact arm being radially and axially rotatable with respect to said frame; a current carrying connection between said frame and said movable contact arm; said contact arm having two internally threaded extensions; a current carrying pin, said pin having a threaded extension at each end; means securing a threaded extension of said pin to said threaded extensions of said contact arm; a cylindrical recess in said frame having a partly threaded surface and a bearing coaxial to said recess; said current carrying pin rotating in said coaxial bearing; a cylindrical contact cup; said cup being externally threaded to engage the threaded surface of said cylindrical recess; means biasing said cup in one direction and effecting a close current carrying engagement between the threads of said cup and of said recess; said cup also having a threaded opening, the other threaded extension of said pin engaging said threaded opening of said cup, means biasing the said other threaded extension of said pin into current carrying engagement with said threaded opening of said cup; means sealing the first of said current carrying connections.

4. A current carrying connection having a fixed and a movable member, one of said members carrying a threaded current carrying pin, the other of said members having a partly threaded cylindrical recess and a bearing coaxial to said recess, said current carrying pin rotating in said coaxial bearing; a cylindrical contact cup; said cup being externally threaded to engage the threaded surface of said cylindrical recess; a set of contact fingers, said contact fingers being connected to said contact cup; said contact fingers being biased into current carrying engagement with said current carrying pin.

5. A current carrying connection having a fixed and a movable member, one of said members carrying a threaded current carrying pin, the other of said members having a partly threaded cylindrical recess and a bearing coaxial to said recess, said current carrying pin rotating in said coaxial bearing; a cylindrical contact cup; said cup being externally threaded to engage the threaded surface of said cylindrical recess; a set of contact fingers, said contact fingers being connected to said contact cup; said contact fingers being biased into current carrying engagement with said current carrying pin; said cup being removable with respect to the second of said members and providing a ready means for inspection of said contact fingers and said contact carrying pin.

6. A switch having a frame and a movable contact arm; said contact arm being radially and axially rotatable with respect to said frame; a current carrying connection between said frame and said movable contact arm; said contact arm

5 having two internally threaded extensions; a current carrying pin, said pin having a threaded extension at each end; means securing a threaded extension of said pin to said threaded extensions of said contact arm; a cylindrical recess in said frame having a partly threaded surface and a bearing coaxial to said recess; said current carrying pin rotating in said coaxial bearing; a cylindrical contact cup; said cup being externally threaded to engage the threaded surface of said cylindrical recess; means biasing said cup in one direction and effecting a close current carrying engagement between the threads of said cup and of said recess; said cup also having a threaded opening, the other threaded extension of said pin engaging said threaded opening of said cup, means biasing the said other threaded extension of said pin into current carrying engagement with said threaded opening of said cup; said cup being removable with respect to the second of said members and providing a ready means for inspection of said current carrying connections; means sealing the first of said current carrying connections.

25 7. A current carrying connection having a fixed and a movable member, one of said members carrying a threaded current carrying pin, the other of said members having a partly threaded cylindrical recess and a bearing coaxial to said recess, said current carrying pin rotating in said coaxial bearing; a cylindrical contact cup; said cup being externally threaded to engage the threaded surface of said cylindrical recess; a set of contact fingers, said contact fingers being connected to said contact cup; said contact fingers being biased into current carrying engagement with said current carrying pin; said cup being removable with respect to the second of said members and providing a ready means for inspection of said contact fingers and said contact carrying pin; means sealing and protecting said current carrying connections.

45 8. A current carrying connection having a fixed and a movable member, one of said members carrying a threaded current carrying pin, the other of said members having a partly threaded cylindrical recess and a bearing coaxial to said recess, said current carrying pin rotating in said coaxial bearing; a cylindrical contact cup; said cup being externally threaded to engage the threaded surface of said cylindrical recess; a set of contact fingers, said contact fingers being connected to said contact cup; said contact fingers being biased into current carrying engagement with said current carrying pin; said cup being removable and replaceable with respect to the second of said members and providing a ready means for inspection of said contact fingers and said contact carrying pin.

60 9. A switch having a frame and a movable contact arm; said contact arm being radially and axially rotatable with respect to said frame; a current carrying connection between said frame and said movable contact arm; said contact arm having two internally threaded extensions; a partly threaded current carrying pin; means securing the threaded part of said pin to said threaded extensions of said contact arm; a cylindrical recess in said frame having a partly threaded surface and a bearing coaxial to said recess; said current carrying pin rotating in said coaxial bearing; a cylindrical contact cup, said cup being externally threaded to engage the threaded surface of said cylindrical recess; means

for electrically connecting said current carrying pin to said cylindrical contact cup.

10. A switch having a frame and a movable contact arm; said contact arm being radially and axially rotatable with respect to said frame; a current carrying connection between said frame and said movable contact arm; said contact arm having two internally threaded extensions; a current carrying pin, said pin having a threaded extension at each end; means securing a threaded extension of said pin to said threaded extensions of said contact arm; a cylindrical recess in said

frame having a partly threaded surface and a bearing coaxial to said recess; said current carrying pin rotating in said coaxial bearing; a cylindrical contact cup; said cup being externally threaded to engage the threaded surface of said cylindrical recess; a current carrying connection between said current carrying pin and said cylindrical contact cup.

GUSTAVE E. HEBERLEIN.
